UNITED STATES PATENT OFFICE.

WILLIAM J. SEITZ, OF GRAPE, MICHIGAN

FRICITION-GEAR.

No. 843,634.

Specification of Letters Patent.

Patented Feb. 12, 1907.

Application filed August 10, 1906. Serial No. 330,672.

To all whom it may concern:

Be it known that I, WILLIAM J. SEITZ, a citizen of the United States, and a resident of Grape, in the county of Monroe and State of Michigan, have invented a new and Improved Friction-Gear, of which the following is a specification.

My invention relates to frictional change-speed gearing adapted for use on motor-driven vehicles and boats and in connection with machines where changes in speed and direction of movement are necessary.

My invention consists generally of a power-shaft having a friction-disk secured thereto, friction-wheels mounted in pairs adapted to engage the disk alternately, each pair so mounted that its wheels engage opposite sides of the disk; means to select the pair to be in engagement with the disk; means to connect the friction-wheels to a driven shaft, and means to control the speed of the driven shaft.

My invention is embodied in the construction illustrated in the accompanying drawings, in which—

Figure 1 is a plan, Figs. 2 and 3 views of opposite sides, and Fig. 4 a front view of the entire mechanism. Figs. 5 and 6 are details of the friction-wheels.

Similar reference characters refer to like parts throughout the several views.

In the drawings, 1 is the frame of a change-speed mechanism, which frame may be built separately to suit any desired installation or as a part of the general frame of the driving machinery. Extending across this frame is a bar or brace 2, which carries the rear bearing 3 of the driving-shaft 4, the front bearing 5, carried by the frame, also serving for this shaft, which may be actuated by any prime motor in any desirable manner. On the rear end of this shaft is secured the friction-disk 6, which may be of any desirable material or construction.

Secured to the frame 1, just in the rear of the brace 2, are the eccentric boxes 7, each provided with a spherical bore, and in each of which is mounted a part sphere 8, which furnish eccentric bearings for the shaft 9. It will be seen from Figs. 2 and 3 that by turning these bearings 8 in the boxes 7 the ends of the shaft 9 will be moved toward and from the disk 6. As will be explained later, the levers to turn these bearings are so arranged

that they turn in opposite directions, so that

while one end of the shaft approaches the disk 6 the other recedes from it.

Mounted on the frame 1 in the brackets 10 is a rod 11, which may be turned by means of the lever 12. Extending down at one end of the rod 11 is the arm 13, and extending upward at the other end is the arm 14. Levers 15 and 16 are secured to the eccentric bearings 8 and are connected, respectively, to the arms 13 and 14 by means of the links 17 and 18. If, then, this lever 12 be swung toward the rear, the link 17 and the lower end of the lever 15 will move forward, and with them the friction-wheel 19 on that portion of the shaft 9, while at the same time the arm 14, and with it the link 18 and lower end of the lever 16, moves to the rear, carrying with them the friction-wheel 20 on that portion of the shaft 9. Moving the lever 12 forward first disengages the wheel 19 from the disk 6, both wheels 19 and 20 being disengaged when the lever 12 is in its central position. Continued forward movement of the lever 12 continues to turn the eccentric boxes 8 until the wheel 20 engages the friction-disk 6. Fig. 1 shows the parts in central position.

Slidably mounted on the frame 1 are two bearing-boxes 21 and 22, which are respectively connected to the eccentricities 8 by means of the links 23 and 24. As the eccentric bearings to which these links respectively connect have opposite movements the action of the links will be to move the ends of the shafts 25 in opposite directions from the ends of the shaft 9, and so move the wheels 20 and 26 toward and from the disk 6 simultaneously, while at the same time the wheels 19 and 27 are moved simultaneously in the opposite directions. By these connections the movements of the lever 12 toward the rear causes the wheels 19 and 27 to engage opposite sides of the disk 6, while a forward movement of the lever will cause these wheels to disengage and the wheels 20 and 26 to engage the disk.

Extending rearward from the front cross-bar of the frame is a plate 30, upon which are slidably mounted the bearings 31 and 32 for the inner ends of the shafts 25. A lever 33 is pivoted at 34 on the plate 30 and connects to these bearings by means of pins 35. The free end of the lever 15 connects to the upper end of the lever 33 by means of the link 36. The action of this mechanism is that when the eccentric bearings 8 turn to

swing the wheels 19 and 27 into contact with the disk 6 the lever 15, swinging rearwardly, will pull the free end of the lever 33 and the bearing 32 toward the rear at the same time that the box 22 moves toward the rear. The result is that the shafts 25 are always substantially parallel to the face of the disk 6 and that the bearings 21, 22, 31, and 32 are always in alignment. A bearing 37 at the front end of the plate 30 serves to render this construction rigid with reference to the shaft 4.

In bearings 40 on the rear end of the frame is mounted the driven shaft 41, having a transmission-gear 42 of any desired type secured thereto and also having sprocket-wheels 43 mounted thereon. The shaft 9 has two sprocket-wheels 44, and each shaft 25 a sprocket-wheel 45 of the same size as wheels 44. A sprocket-chain 46 passes around each wheel 45, thence to the wheel 43, and over around the same and back over a wheel 44. In this manner the revolution of the shafts 25 and 9 in opposite directions is provided for.

With constant speed of shaft 4 it is often desirable that the shaft 41 shall have variable speed. To accomplish this, I have provided means to move the wheels 19 and 27 radially of the shaft 4. A rod 50 is mounted in the brace 2 and on the bracket 51 at the front end of the frame 1. This bracket carries a screw 52, having a crank-handle 53 to turn the same. On the rod 50 is mounted an arm 54, which has pivoted at its free end a nut 55 on the screw 52. When, therefore, the screw 52 is turned by means of the handle 53, the rod 50 will turn in its bearings and will swing the lower forked ends of the arms 56 that are secured to the rod. With this movement of the arms 56 the friction-wheels 19 and 27 will move radially of the shaft 4, and so turn at increased or decreased speeds with reference to this shaft as their distance from this shaft increases or decreases.

When the rim of a cylindrical friction-wheel contacts with a friction-disk, the portion of the rim farthest from the center of the disk will travel at the same speed as the portions of the rim nearer to the center, while the circular rings of the disk in contact with various portions of the rim of the wheel will travel at speeds varying as their distances from the center. The result of this is that parts of the rim will lag and other parts lead the portions of the disk in contact therewith in speed. This will cause undesirable friction and waste of power, and hence wear. To form the friction-wheel as tapering as possible in the most effective manner to overcome the greatest possible portion of these defects, and the amount of taper possible will depend upon the mounting of the friction-wheels.

The shafts 9 and 25 are provided with feathers 60, upon which shafts and feathers are slideable the hubs 61. The hub has a spherical portion 62, upon which is mounted a friction-wheel 19 or 27, being secured in place by the collar 63. A feather 64 on the other spherical portion 62 prevents the disk 27 from turning on the hub, but permits it to swing laterally. A collar 65 is secured onto the end of the hub 61 after the collar 63 has been slipped on, which collar 63 and 65 are provided with grooves to receive the inwardly-extending flanges 66 on the two-part sleeve 67. The sleeves 67 are wedge-shaped and are provided with trunnions 68, which are engaged by the lower ends of the arms 56. By these means the conical friction-wheels 19 and 27 are constantly held in proper position.

To prevent the shaft 9 from moving too far and thus swinging the bearings 8 in the boxes 7 more than necessary, I provide pins 70 and 71, mounted on the frame in the rear of the levers 15 and 16, and to permit full stroke of the lever 12 and arms 13 and 14 I provide the links 17 and 18 with slots 72 in their forward ends. The loose washers 74 and springs 75 serve to hold the ends of the arms 13 and 14 in position; but the springs are not stiff enough to prevent the arms 95 moving to the rear when the links are stopped by the pins 70.

Having now explained my improvements, what I claim as my invention, and desire to secure by Letters Patent, is—

1. In a friction-gear, the combination of a driving-shaft, a friction-disk mounted thereon, a frame to support said shaft, a second shaft mounted on said frame substantially parallel to one face of the disk, a pair of friction-wheels mounted on said second shaft, the ends of said shaft being so mounted as to be movable toward and from the face of said disk and thereby carry one or the other of said friction-wheels in contact therewith, with a driven shaft, and gearing connecting said second shaft to said driven shaft.

2. In a friction-gear, the combination of a driving-shaft, a friction-disk mounted thereon, a frame to support said shaft, a second shaft mounted on said frame substantially parallel to one face of the disk, a pair of friction-wheels mounted on said second shaft, the ends of said shaft being so mounted as to be movable toward and from the face of said disk and thereby carry one or the other of said friction-wheels in contact therewith, and thereby determine the direction of revolution of said second shaft, means to move the ends of said shafts in opposite directions at the same time, a driven shaft, and gearing connecting said second shaft to said driven shaft.

3. In a friction-gear, the combination of a driving-shaft, a friction-disk mounted there-

on, a frame to support said shaft, a second shaft mounted on said frame substantially parallel to one face of the disk, a pair of friction-wheels mounted on said second shaft,

5 the ends of said shaft being so mounted as to be movable toward and from the face of said disk and thereby carry one or the other of said friction-wheels in contact therewith, eccentric boxes for the ends of said shaft, a lever mounted on said frame, connections between said lever and said boxes whereby the actuation of said lever will move the ends of said shaft in opposite directions, a driven shaft, and gearing connecting said second 15 shaft to said driven shaft.

4. In a friction-gear, the combination of a frame, a driving-shaft mounted thereon, a friction-disk secured to said shaft, a second shaft mounted on said frame across the rear face of the disk, a friction-wheel mounted on said second shaft on each side of the driving-shaft, a pair of shafts axially mounted on said frame across the front face of the disk, a friction-wheel mounted on each shaft and respectively opposite the friction-wheels on the second shaft, and means to move the wheel-carrying shafts laterally in such a manner that the pairs of friction-wheels may alternately separate and approach each 30 other, thereby forming an operative contact between the wheels on either side of the driving-shaft and the friction-disk.

5. In a friction-gear, the combination of a frame, a driving-shaft mounted thereon, a friction-disk secured on said shaft, a second shaft mounted on said frame across one face of said friction-disk, a friction-wheel mounted on said second shaft on each side of the driving-shaft, a pair of shafts axially mounted on 40 said frame across the other face of said friction-disk, one shaft on each side of the driving-shaft, a friction-wheel mounted on each of these shafts and opposite to and forming pairs with the friction-wheels on the second shaft, and means to cause the pair of friction-wheels on one side of the driving-shaft to engage the friction-disk while the pair on the other side of the driving-shaft are separated from said disk.

50 6. In a friction-gear, the combination of a frame, a driving-shaft mounted thereon, a friction-disk secured on said shaft, a second shaft mounted on said frame across one face of said friction-disk, a friction-wheel mounted on said second shaft on each side of the driving-shaft, a pair of shafts axially mounted on said frame across the other face of said friction-disk, one shaft on each side of the driving-shaft, a friction-wheel mounted on each of these shafts and opposite to and forming pairs with the friction-wheels on the second shaft, and means to cause the pair of friction-wheels on one side of the driving-shaft to engage the friction-disk while the pair on the other side of the driving-shaft are separated 65

from said disk, and means to slide one pair of wheels radially of the driving-shaft to control the speed of the second shaft.

7. In a friction-gear, the combination of a frame, a driving-shaft mounted thereon, a friction-disk secured to said driving-shaft, a second shaft mounted on said frame substantially parallel with a face of said disk, a grooved hub slidable on the second shaft and revoluble therewith, said hub provided with a spherical portion, a friction-wheel mounted on said spherical portion and adapted to revolve therewith but permitted to swing thereon, said wheel provided with a grooved collar, and a sleeve whose ends are at an angle to each other and provided with flanges to engage in the grooves in said hub and collar, and a lever in engagement with said sleeve whereby the angle between the plane of the wheel and its shaft is kept constant. 85

8. In a friction-gear, the combination of a frame, a driving-shaft mounted thereon, a friction-disk secured to said driving-shaft, a second shaft mounted on said frame substantially parallel with a face of said disk, a grooved hub slidable on the second shaft and revoluble therewith, said hub provided with a spherical portion, a friction-wheel mounted on said spherical portion and adapted to revolve therewith but permitted to swing thereon, said wheel provided with a grooved collar, and a sleeve whose ends are at an angle to each other and provided with flanges to engage in the grooves in said hub and collar, and a lever in engagement with said sleeve whereby the angle between the plane of the wheel and its shaft is kept constant, 95

9. In a friction-gear, the combination of a frame, a driving-shaft, a friction-disk mounted on the same, eccentric bearings on said frame, a second shaft mounted therein and across one face of the disk, friction-wheels mounted on said shaft and adapted to alternately contact with said disk, a pair of shafts mounted across the other face of the disk, slidable bearings for said shafts, a friction-wheel mounted on each shaft opposite a wheel on the second shaft, connections between the eccentric bearings and said slidable bearings, and operating means comprising levers and links whereby the forward movement of the operating-lever will cause one pair of wheels to engage the disk and its rearward movement will cause the engagement of the other pair of wheels and the disk. 105

In testimony whereof I sign my name in the presence of two subscribing witnesses,

WILLIAM J. SEITZ.
